COMBINED VENTILATION FAN BANK AND LIGHT BAFFLE FOR POULTRY BUILDING

George E. France, Rte. 2, Box 60, Oswego, Ill. 60543

Filed May 8, 1972, Ser. No. 51,603

Term of patent 14 years

Int. Cl. D23—04

U.S. Cl. D23—140

FIG. 1 is a front elevation of a combined ventilation fan bank and light baffle for poultry building, embodying my new design.

FIG. 2 is a top plan view of the combined ventilation fan bank and light baffle for poultry building, shown in FIG. 1.

FIG. 3 is an end elevation of the combined ventilation fan bank and light baffle for poultry building, shown in FIG. 1 and FIG. 2.

FIG. 4 is another end elevation of the combined ventilation fan bank and light baffle for poultry building, showing the end opposite to that of FIG. 3.

FIG. 5 is a cross-sectional view thereof taken on line 5—5 of FIG. 1.

FIG. 6 is a partial cross-sectional view thereof taken on line 6—6 of FIG. 2.

FIG. 7 is a fragmentary rear elevational view thereof, the housing being broken away for convenience of illustration.

FIG. 8 is a fragmentary perspective view of the baffles which appear in the rear elevational view in FIG. 7.

FIG. 9 is a fragmentary perspective view taken from the other side of the baffles of FIG. 8.

The baffles in FIGS. 8 and 9 are fragmentarily shown for convenience of illustration; the housing is omitted in FIGS. 8 and 9 for a complete disclosure of the baffles.

I claim:

The ornamental design for combined ventilation fan bank and light baffle for poultry building, as shown and described.
